P. W. Toy
Temporary Binder
No. 20,670. Patented Jun. 22, 1858.

UNITED STATES PATENT OFFICE.

P. W. TOY, OF NEW YORK, N. Y.

PORTEFOLIO-FILE.

Specification of Letters Patent No. 20,670, dated June 22, 1858.

To all whom it may concern:

Be it known that I, PETER W. Toy, of New York city, New York, have invented a new and Improved Portfolio-File; and I do hereby declare the following to be a correct description of the same, reference being had to the accompanying drawing, which represents the portfolio lying open with a piece of music filed in it.

10 The nature of my invention consists in combining with a portfolio and file for music, papers, &c., a contrivance for holding down the leaves of music while playing, and a device for converting the portfolio into a

15 perfect bound book when full.

In the drawing the letters A A mark the sides of the portfolio; B B the back of the same; C the metallic rod or guard for confining the music, &c., on the cords; D D the 20 cords on which the music, &c., is filed; d, d, the holes in rod C through which the cords pass; E, E, the elastic bands for holding down the leaves of the music when turned over; F F the loops for completing the 25 binding when the file is full.

The sides and back A, B, of the portfolio are finished in any style that may be preferred. For music I have found plush and velvet well adapted as they do not scratch 30 the highly polished surface of the piano or other instrument on which they may be placed.

The file is formed by two cords attached 35 to the right of the back of the portfolio at the points indicated by d, d, and passing

through holes in rod C at those two points. The music, &c., to be filed, is strung on to these cords, perforations having been previously made at the proper points, and the ends of the cords passed through rod C and 40 tied together. When it is desired to hold down a leaf, it is passed under the elastic band on either side. An index is placed as shown on the inside of the left hand cover. When a sufficient quantity of matter has 45 been filed to be equal in thickness to the width of the back B of the portfolio, the rod C is glued down and the cords D, D, passed through the loops F, F, and securely and permanently fastened, when a com- 50 pletely bound volume is produced.

Having thus described my invention, I wish it to be understood that I do not claim separately the sides and back A, B, or the mode of filing by the cords D, D, and rod 55 C, but

I do claim—

1. Separately the elastic bands E, E, and the loops F, F, arranged and operating as 60 described.

2. I also claim the combination of the portfolio cover with the file, loops and bands substantially as described, as forming a new, convenient and useful article.

The above specification signed and witnessed this second day of June 1858.

P. W. TOY.
